LIQUID FUEL INJECTION SYSTEMS FOR INTERNAL COMBUSTION ENGINES

Wilfrid Edward Walter Nicolls, Pinner, England, assignor to C.A.V. Limited, London, England

Application May 27, 1957, Serial No. 661,690

Claims priority, application Great Britain May 30, 1956

6 Claims. (Cl. 123—139)

This invention relates to liquid fuel injection systems for internal combustion engines which at each injection require to be supplied with a considerable volume of fuel at high pressure.

A system in accordance with the invention includes a fuel metering pump adapted to be driven by the engine, an injection pump which is fed by the metering pump and is adapted to effect its discharge by the action of engine cylinder air compression pressure, and a valve operable by pressure of the fuel supplied by the metering pump for controlling the discharge of the injection pump.

The metering pump may be of any convenient variable-delivery type which is supplied by a feed pump and is adapted to be driven through a mechanical connection with a rotary part of the engine. This pump may be of the reciprocating plunger type having a plurality of plungers corresponding to the number of cylinders in the engine. Alternatively it may be of the distributor type wherein a single pumping means is adapted to supply each cylinder of the engine in turn through a rotary distributor.

In the accompanying drawing:

Figure 1 is a sectional side elevation of a liquid fuel injection system according to the invention.

Figures 2 and 3 are similar views to Figure 1 illustrating respectively two further embodiments of the invention.

In the example shown in Figure 1 the metering pump comprises a plurality of reciprocating plungers as 3, according to the number of cylinders in the engine. Each plunger is contained in a cylinder 4, the suction strokes of the plunger being affected by a spring 5, and the delivery strokes by an engine-driven rotary cam 6 acting through a slider 7 carrying a roller 8. The fuel is supplied by a feed pump to the inlet 9, and from the inlet the fuel can enter the cylinder through a port 10. Discharge of the fuel by the plunger is effected through a non-return valve 11 loaded by a spring 12, the fuel being conveyed by a pipe 13 to the injection pump. Relief of pressure in the said pipe for the purpose hereinafter mentioned is effected by a second valve 14 loaded by a spring 15 and arranged between the said pipe and a return passage 16, which is controlled by the plunger. In each discharge stroke of the plunger the first effect of the plunger is to close the port 10. For varying the amount of the discharge the instant at which the port is closed is variable by a substantially V-shaped notch 17 in the plunger. The position of this notch relatively to the port is variable by rotation of the plunger, this being effected by a toothed rack 18 which is operable by a speed governor or manually, and which engages a toothed segment 19 on the plunger.

The injection pump comprises a cylinder 20, containing a plunger 21, which is actuated by a mechanism responsive to cylinder air pressure at or near the end of a compression stroke, an injection pump being provided for each of the engine cylinders. In the example illustrated, the discharge stroke of the injection pump

2

plunger is effected through a rocker lever 22 one end of which acts on the plunger through a slider 23, loaded by a spring 24, the other end of the lever being connected by a rod 25 to a piston 26 in a cylinder 27 communicating with the engine cylinder, the piston being loaded by a spring 29. The arrangement is such that the pressure in the engine cylinder when its piston 28 approaches the inner end of its stroke is utilized for moving the plunger-actuating piston 26 against the action of the associated spring 29 for effecting the discharge stroke of the injection plunger, the return stroke of the actuating piston being effected by the spring.

For controlling a passage 30 between the cylinder of the injection pump and the injection nozzle 31 in the engine, there is provided a piston valve 32 loaded by a spring 33 and contained in a cylindrical bore which is connected by a passage 34 to the pipe 13. On the valve is formed a circumferential groove 35 which when the valve is in its open position as shown interconnects adjacent parts of the passage 30. For limiting the extent of axial movement of the valve in one direction, the valve is provided at one end with a flange 32a which, when the valve is in its open position, is caused by the loading spring 33 to bear against a shoulder at one end of the bore containing the valve. Also between the opposite end of the bore containing this valve and the cylinder of the injection pump is provided a valve 36 loaded by a spring 37 through which the fuel supplied by the metering pump to the passage 34 can enter the injection pump.

The injection nozzle contains a valve 38 which is loaded by a spring 39. This valve controls the outlet of the nozzle, and is raised off its seating by pressure of the fuel discharged from the injection pump.

The arrangement is such that in each delivery stroke of the metering pump, the first effect of the pressure of the discharged fuel is to move the piston valve 32 against the action of the spring 33 to its shut position on which it obstructs the passage 30. The fuel discharged by the metering pump then passes through the valve 36 to the injection pump. During the following suction stroke of the metering pump the passage 16 is uncovered by the plunger 3 and the resulting fall of pressure in the part of the system between the two pumps allows the spring 33 acting on the piston valve 32 to return it to its open position, and in this movement of the valve the fuel displaced thereby is returned to the metering pump inlet. The engine pressure then causes the plunger of the injection pump to discharge the contents of this pump to the fuel injection nozzle. When the engine cylinder is opened to exhaust the piston 26 which acts on the injection pump plunger is returned to its initial position by its spring in readiness for the next cycle of action.

In the alternative arrangement of the invention shown in Figure 2, there is combined with the system, and conveniently in combination with the injection pump, an accumulator comprising a piston 40 contained in a cylindrical bore and loaded by a spring 41, one end of the bore being in communication with the passage 34. In this arrangement the valve 32 initially occupies the shut position as shown in which it obstructs the passage 30. Further the metering pump is provided only with the above described discharge valve 11, loaded by a spring 12, the valve 14 being not required.

When the system is in action, the first effect of the pressure of the fuel in each discharge from the metering pump is to move the valve 32 against the action of the spring 33 to its open position in which it allows the previously charged injection pump to discharge its content to the nozzle 31 under the action of engine pressure. Meanwhile the metering pump charges the accumulator.

After the injection pump has performed its duty and while the metering pump is drawing in a new charge, the accumulator discharges its content to the injection pump.

In the further alternative arrangement shown in Figure 3, the injection pump and the injection nozzle are constructed as separate components, for enabling the invention to be used in conjunction with any suitable nozzle of standard form. The injection pump comprises a plunger 21² contained in a cylinder 20² which is adapted to be accommodated in a cylinder 27². Within the cylinder 27² is contained a piston 26² which is loaded by a spring 29² and is movable against the action of the spring by the pressure in the engine cylinder, the piston being arranged to act directly on the plunger 21². Above the cylinder 20² is mounted a valve box 44 containing the piston valve 32² which is loaded by a spring 33². Liquid fuel is conveyed from the metering pump by a pipe 13 to the part of the bore in the valve box between one end of the valve 32² and the valve 36², and is supplied to the cylinder 20² through the valve 36². At the same time the incoming fuel moves the valve 32² to the position at which it isolates the cylinder 20² and passage 30² from the pipe 45 whereby the valve box is connected to the injection nozzle.

The arrangement is such that after the cylinder 20² has received its charge of fuel from the metering pump the valve 32² returns to the position shown under the action of the spring 33², and subsequently this charge is delivered to the nozzle by the action of the piston 26² on the plunger 21².

The injection nozzle may be of any convenient and suitable form. In the example illustrated it consists of a hollow body part 46 containing an outlet-controlling closure member 38² which is loaded by a spring 47 acting through a stem 48. In the part 46 is formed a passage 30³ which conveys the fuel from the pipe 45 to the lower end of the closure member 38² the latter being moved upwardly by the pressure of the fuel acting in opposition to the spring 47 for opening the discharge outlet of the nozzle.

The metering pump is similar to that already described with reference to Figure 1, the various parts being indicated by the same reference numerals as those employed in Figure 1.

By this invention the duty imposed on the metering pump is solely that of delivering measured quantities of fuel at relatively low pressure. The duty of discharging the fuel to the engine at high pressure is performed by the injection pump. Consequently the actuating means of the metering pump is not subjected to a heavy load, and is therefore not liable to be deranged by excessive wear or strain. Moreover the actuating means of the injection pump is of a simple and robust character which can readily be made to withstand the duty imposed on it.

Having thus described my invention what I claim as new and desire to secure by Letters Patent is:

1. A liquid fuel injection system for an internal combustion engine in which air is compressed preparatory to the injection thereinto of liquid fuel, comprising in combination a liquid fuel metering pump provided with

actuating means operable by the engine, and with a fuel inlet and a fuel outlet, a liquid fuel injection pump also provided with a fuel inlet and a fuel outlet, fuel-transfer means interconnecting the fuel outlet of the metering pump and the fuel inlet of the injection pump so that the latter can be supplied with liquid fuel by the metering pump through the fuel-transfer means, pressure-responsive means operable by the engine air compression pressure for effecting discharge of the injection pump, and a valve arranged to control the discharge of the injection pump, and to be operated by the pressure of the fuel delivered by the metering pump.

2. A liquid fuel injection system for an internal combustion engine in which air is compressed preparatory to the injection thereinto of liquid fuel, comprising in combination a liquid fuel metering pump provided with actuating means operable by the engine, and with a fuel inlet and a fuel outlet, a liquid fuel injection pump also provided with a fuel inlet and a fuel outlet, fuel-transfer means interconnecting the fuel outlet of the metering pump and the fuel inlet of the injection pump so that the latter can be supplied with liquid fuel by the metering pump through the fuel-transfer means, and pressure-responsive means operable by the engine air compression pressure for effecting discharge of the injection pump, the latter having in combination a plunger operable by the pressure-responsive means, a cylinder in which the plunger is slideable, and to which fuel from the metering pump has access through the fuel inlet of the injection pump, a spring-loaded piston valve arranged to control discharge of fuel from the cylinder through the fuel outlet of the injection pump, and to be moved against its spring loading by the pressure of the fuel delivered by the metering pump, a passage forming the fuel inlet of the injection pump, and arranged to conduct fuel from the metering pump to one end of the piston valve, and a spring-loaded, non-return valve arranged between the said passage and cylinder.

3. A system according to claim 2, in which the piston valve initially occupies an open position, and in which a fuel pressure relief valve controllable by the metering pump is arranged between the latter and the fuel-transfer means.

4. A system according to claim 2, in which the piston valve initially occupies a closed position, and in which a fuel accumulator chargeable by the metering pump is arranged in communication with the fuel inlet of the injection pump.

5. A system according to claim 2, in which the pressure-responsive means comprises a spring-loaded piston movable against its spring loading by the engine air compression pressure, and arranged to act directly on the plunger of the injection pump.

6. A system according to claim 2 and having a fuel injection nozzle in the form of a separate unit connected to the outlet of the injection pump.
